UNITED STATES PATENT OFFICE.

HIGHLAND E. HUSTED, OF GALESBURG, ILLINOIS.

INITIATION APPARATUS.

No. 824,722.

Specification of Letters Patent.

Patented July 3, 1906.

Application filed January 25, 1906; Serial No. 297,874.

To all whom it may concern:

Be it known that I, HIGHLAND E. HUSTED, a citizen of the United States, residing at Galesburg, in the county of Knox and State 5 of Illinois, have invented a new and useful Initiation Apparatus, of which the following is a specification.

My invention relates to initiation apparatus for employment in lodges, secret societies, and wherever such equipment or paraphernalia may be desirable or necessary.

As is well known, the object of an initiation ceremony is to test the courage of the candidate for membership and to impress 15 upon him a deep and lasting impression concerning the mysterious rites and ceremonies, the obligations which he takes, and the duties of the members of the lodge or other organization of which he is about to become a 20 member. To these ends he is put through certain ordeals which are intended to accomplish said objects, but without injury to him of any nature or character whatsoever.

The primary object of my invention is to 25 provide a device of the character described which, while calculated to produce such impressions, is of such construction and organization that its employment in the initiation ceremony cannot result disastrously to the 30 candidate, but may be used with perfect and absolute safety.

I am aware that initiation apparatus for the purposes and of the character hereinbefore described have heretofore been provided; but such of them as have come under 35 my observation have been of such construction that it was with difficulty that they could be assembled or taken apart, (if at all,) such operation being attended by delay and 40 loss of time, a condition which under the circumstances is extremely undesirable, and if they were of such nature that they could not be taken apart they were generally exposed to view and occupied needed space.

A further object of the invention consists 45 in providing a device of the character described which while of large proportions may be readily, easily, and quickly put together and in place, may be quickly taken apart, 50 and may be packed or stored within a small compass or for shipment.

A further object of the invention is to provide an assemblage of parts so disposed and arranged as to give an effect at once pleasing 55 to the eye and adapted to the office each has to perform.

Mechanism embodying the preferred constructive forms of and showing the mutual relationship and combination of the parts forming the subject-matter of my improvements is illustrated in the accompanying drawings, in which all of said parts are shown as constructed and embodied in the best way now known to me. Obviously, however, some of the parts may be altered in their 65 forms, some may be used without the others, and some may be employed in machines differing in construction and arrangement and for different purposes from the one shown in said drawings, in which—

Figure 1 is a side elevation; Fig. 2, a front elevation; Fig. 3, an elevation similar to that shown in Fig. 1, but showing the carriage, with its occupant, as having traversed a portion of its flight after having been released; Fig. 4, a bottom plan of the platform; Fig. 5, a front elevation of the carriage; Fig. 6, a side elevation thereof; Fig. 7, an elevation of the track or runway, and Figs. 8, 9, 10, and 11 details.

Referring now to the drawings by numerals and letters, the same reference character indicating the same part in the different figures thereof, 1 1 represent base-boards or bonds, for a purpose hereinafter described, 85 and form a portion of an inclined track, also hereinafter described.

2 2 are corner posts or stanchions, at the upper end of each of which is a dowel-pin 4.

5 5 are metal braces secured by bolts 5^a at 90 their upper and lower ends, respectively, to the platform B (hereinafter described) and to the posts 2.

B is a platform constructed of end pieces 6, side pieces 7, connecting-strips 8, and a floor 95 9. a b are apertures or sockets in its under side. Other apertures (not shown) are provided in its upper side. Secured to the bottom of the platform by keepers 10 is a latch 11, operated by a lever 12 in an evident manner and for a purpose hereinafter described. 13 is an opening extending entirely through the platform. 13^a represents hooks secured to the rear side of the platform and which are adapted to engage with eyes or staples fixed to 105 the wall and serve to instantly fix the platform thereto or detach it therefrom.

C represents a vertical race or wheel-retaining track or track perpendicular to the line of the horizon comprising parallel bars 110 14, having flanges 15 and through-openings 16. The rear upper portion of each bar is

cut away for the reception of a wall-plate 17, having a central orifice through which is passed a lag-screw 18, by which it is secured to a wall. (Not shown.) A bolt 19 is passed 5 through each orifice or aperture 16 and through apertures in the wall-plate, by which means said parts are firmly held together and the wheel-retaining track to the wall. At the lower end of each bar 14 is a 10 dowel-pin 20.

D is a runway formed of parallel elliptical or otherwise curved and downwardly-inclined bars D', substantially L-shaped in cross-section, comprising a track portion 21 and 15 flanges or guards 22, which bars are united and held in alinement by connecting rods d. At the upper end of each bar is a dowel-pin 23. Near the forward portion of the track, or at that point where it first contacts the 20 floor, it is cut away to form a shoulder 24, which is engaged by one end of a base-board 1, the other end of which is fixed to a strut 25, the distal end of which rests against and supports a shoulder 26 near the upper end 25 of the runway. At the lower end of each strut is a dowel-pin 27, which engages a corresponding aperture in the floor. 28, 29, and 30 are braces and may be of any preferred construction.

30 The wheeled truck or carriage E comprises a bed or body portion 31, provided with padding or upholstery 31^a (see Fig. 2) and having an outwardly-inclined head-rest or pillow 32, which is also padded, (for safety,) a gate 35 or foot-board 33, which when the carriage is in its initial position constitutes a trap-door, braces 34, axles 35, and wheels 36. Hinged to the bed at 37 is a shield 38, preferably of strong wire-netting, which shield is adapted to 40 be swung open to permit the candidate to enter while in an erect position and to afterward be closed and fastened by a latch 39. The means employed for hinging and fastening the latch is immaterial. 40 is a flight of 45 steps by which the platform B may be reached and may be secured thereto by hooks 41 and staples 42 or in any other desired or preferred manner.

The device is with great speed and accuracy and in a rigid manner assembled as follows: The frame A, having first been put together by means of the bolts 5^a and braces 5, it and the runway D are brought into their proper relative positions on the floor and the 55 dowel-pins 27 in the struts inserted in sockets in the floor already prepared for their reception. The platform B is then raised into position with the dowel-pins 4 resting snugly in the sockets a and the pins 23 in the sockets b, 60 whereupon the hooks 13^a are engaged with the wall-staples, (not shown,) by which several means said parts A, B, and D are securely and safely fixed in place and to each other. The vertical wheel-retaining track, 65 with its attached wall-plate, being then raised

into position, with the dowel-pins 20 projected into sockets in the upper surface of the platform and the plate 17 contacting the wall, the lag-screw is threaded thereinto and the entire device held securely and fixedly in 70 rigid position and in a remarkably short time. A reverse operation, it will be evident, will in a very brief time and with great ease take the device apart, whereupon it may be stored or packed for shipment in a com- 75 paratively small space.

The machine or apparatus having been assembled as above described and it being desirable to place the carriage in position for use, the wheels thereof may be introduced 80 upon the inclined track or runway with the head-rest forward. It will be manifest that the inclined pillow will permit that end thereof to traverse its path without contacting the curvature of the track, nor indeed any portion thereof. The trap-door 33, of a size only sufficient to enter the opening or gateway 13, having reached the position shown at Figs. 1 and 2 the lever 12 is given a throw to thrust the latch 11, which had prepara- 85 tively been opened, to the position shown at Fig. 4, whereby the carriage will be securely held from downward movement in the position shown at said figures. The wheels 36 will be confined by and within the flanges 15 90 and the carriage prevented thereby from falling outwardly or forwardly therefrom. The apparatus being then in readiness, the blindfolded candidate is conducted, by means of the stairway, to the platform, and thence to 95 the trap-door 33, his back and head resting against the padded body and pillow of the carriage. The shield is then closed and latched or locked in such manner that the arms of the occupant are pinioned closely to his body, whereupon the lever is thrown in a direction contrary to that last described to 100 withdraw the latch, and thereby release the trap-door. The carriage and its occupant will by force of gravity be dropped with great 105 speed through the opening 13 first in a perpendicular and then in the direction of the curvature of the runway D, the carriage-wheels being retained during their flight 110 through the race C by the flanges 15. The 115 first impulse of the occupant is to throw his hands and arms outwardly. This would result disastrously as he passed through the opening 13 were it not prevented by the shield, which, as hereinbefore described, pinions his arms closely to his body. The padding or upholstery effectually prevents injury to his person no matter how great his 120 struggles for release. The carriage having passed from a vertical to an inclined position, 125 there is no longer need for confinement of the wheels. The open flanged track is therefore provided. The carriage having passed therefrom and onto the floor, it, if it does not stop by reason of friction, may be caught by mem- 130

bers of the lodge and the occupant released from his recumbent position by releasing the shield 38.

It will be evident that the device may be employed with absolute safety and that no harm can possibly result from its use. It is effective in that a considerable fright is given the candidate, sufficient, in fact, to accomplish the objects sought. It presents an attractive appearance when assembled, and its construction is such that it may readily be packed away or shipped from one lodge to another.

Although I have specifically described the construction and relative arrangement of the several parts of my improvements, yet I do not desire to be confined to such specific constructions, as such changes or modifications may be made as fairly fall within the pur-

view of my invention.

What I claim as new, and desire to secure by Letters Patent, is—

1. In an initiation apparatus, an upper, perpendicular wheel-retaining track and a lower, inclined runway.

2. In an initiation apparatus, an upper, perpendicular wheel-retaining track and a lower, flanged runway.

3. In an initiation apparatus, an upper, perpendicular, wheel-retaining track, a lower, inclined runway, and means for connecting them.

4. In an initiation apparatus and in combination, a wheeled carriage, an upper, perpendicular track, means for holding the wheels of the carriage therein, and a lower, inclined runway.

5. In an initiation apparatus and in combination, a wheeled carriage, an upper, perpendicular track, means for holding the carriage-wheels therein, and a lower, inclined runway.

6. In combination with a gravity-operated wheeled carriage, an upper, perpendicular wheel-retaining track and a lower, inclined runway.

7. In combination, an upper, vertical wheel-retaining track provided with flanges in pairs, a lower, inclined runway, a gravity-operated wheeled carriage, and means for retaining it in a suspended position and for releasing it therefrom.

8. The combination with a frame, a platform supported thereon and provided with a gateway, an upper, vertical wheel-retaining track and a lower, inclined runway, of a carriage adapted to pass over said track and runway and through said gateway.

9. The combination with a platform provided with a gateway, an upper, vertical wheel-retaining track and a lower, inclined

runway, of a carriage adapted to pass over said track and runway and through said opening, and means for maintaining said carriage in a suspended position partly within 65 said gateway and for releasing it therefrom.

10. In combination, a frame, a platform supported thereon having an enlarged opening, an upper, vertical, wheel-retaining track and a lower, inclined runway, a gravity-oper- 70 ated carriage adapted to pass through said opening, means for holding it partly within said opening and for releasing it.

11. In a device of the character described, a frame, dowel-pins on the upper ends of the 75 posts thereof, a platform having a gateway, supported thereon, an inclined runway provided with dowel-pins seated in sockets in the lower portion of said platform, a vertical track provided with dowel-pins seated in 80 sockets in the upper portion of said platform, and a plate fixed to said last-named track.

12. In a device of the character described, a rectangular frame comprising corner posts and braces between each pair thereof, an inclined runway within said frame, means for supporting it a platform having an opening therethrough, supported by said frame and track, and a vertical track supported by said platform.

13. In an initiation apparatus, a rectangular frame comprising a plurality of posts, braces fixed to each pair thereof, dowel-pins in the upper ends thereof, an inclined runway, dowel-pins at the upper end thereof, 95 base-boards and struts fixed to said runway, dowel-pins at the lower ends of the struts, a platform provided with a gateway and having sockets in its lower portion, said sockets engaged with said pins and said platform 100 mounted on said frame and runway.

14. In an initiation apparatus, a rectangular frame comprising a plurality of posts, braces fixed to each pair thereof, a dowel-pin in the upper end of each post, an inclined 105 runway, dowel-pins at the upper end thereof, struts fixed to said runway, dowel-pins at the lower ends thereof, a platform provided with a gateway and having sockets in its lower portion, said sockets engaged with said pins 110 and said platform mounted on said frame and runway, an upper, wheel-retaining track, a dowel-pin at the lower end of each rail thereof, said pins engaged with sockets in the upper portion of said platform, and a plate 115 fixed to and connecting the rails of said track.

In testimony whereof I have hereunto set my hand this 20th day of January, 1906.

HIGHLAND E. HUSTED.
